NOZZLE FOR OXYGEN LANCES

Leland H. Hutton, University Heights, Ohio, assignor to
Hutton Fabricating Manufacturing Corp., Cleveland,
Ohio, a corporation of Ohio

Filed Feb. 6, 1961, Ser. No. 63,824

Term of patent 14 years

(Cl. D91—1)

Fig. 1

Fig. 2

Fig. 3

Fig. 4

FIG. 1 is a side elevational view of a nozzle for oxygen lances embodying my new design;

FIG. 2 is a top plan view;

FIG. 3 is a bottom plan view; and

FIG. 4 is a vertical cross-sectional view thereof.

I claim:

The ornamental design for a nozzle for oxygen lances,
as shown.
